UNITED STATES PATENT OFFICE.

LOYD W. RAY, OF WICHITA, KANSAS.

DESIGN FOR A VEHICLE-BODY.

58,257.

Specification for Design.

Patented June 28, 1921.

Application filed March 5, 1921. Serial No. 450,106. Term of patent 14 years.

To all whom it may concern:

Be it known that I, LOYD W. RAY, a citizen of the United States, residing at Wichita, in the county of Sedgwick and State of Kansas, have invented a new, original, and ornamental Design for Vehicle-Bodies, of which the following is a specification, reference being had to the accompanying drawing, forming part thereof.

Figure 1 is a side elevation of a vehicle body, showing my new design.

Fig. 2 is an end elevation thereof.

I claim:

The ornamental design for a vehicle body, as shown.

LOYD W. RAY.
